Primary Examiner — Paula Greene(74) *Attorney, Agent, or Firm* — Plumsea Law Group, LLC(57) **CLAIM**

The ornamental design for a loudspeaker system, as shown and described.

DESCRIPTION

FIG. 1 is a perspective view of a loudspeaker system showing our new design;

FIG. 2 is a rear perspective view thereof;

FIG. 3 is a front elevational view thereof;

FIG. 4 is a rear elevational view thereof;

FIG. 5 is a side elevational view thereof, the opposite side elevational view being a mirror image thereof;

FIG. 6 is a top view thereof;

FIG. 7 is a top view thereof, shown with the top cover in a pivoted open position;

FIG. 8 is a rear elevational view thereof shown with the top cover in a pivoted open position; and,

FIG. 9 is a perspective view of another embodiment of a loudspeaker system showing our new design, shown with a column tweeter mounted on the main body housing, and the top cover in a closed position.

The broken line showing depicts environmental features and forms no part of the claimed design.

1 Claim, 9 Drawing Sheets(56)
